UNITED STATES PATENT OFFICE.

ABELARDO G. DE AGUIAR, OF HAVANA, CUBA.

BAGASSE DRIER AND FURNACE.

SPECIFICATION forming part of Letters Patent No. 380,999, dated April 10, 1888.

Application filed June 21, 1887. Serial No. 242,023. (No model.)

To all whom it may concern:

Be it known that I, ABELARDO G. DE AGUIAR, a subject of the Queen of Spain, and a resident of Havana, Cuba, have invented 5 a new and useful Bagasse Drier and Furnace, of which the following is a specification.

The few attempts to dry the bagasse by a furnace have been but partially successful.

The object of my invention, therefore, is to 10 provide an apparatus adapted to operate in connection with a sugar-mill which will receive the bagasse or refuse cane as it leaves the mill, and by means of a suitable construction convey it around or over the boilers so that the 15 heat from the said boilers will cause the moisture in the bagasse or refuse cane to evaporate. By this means the bagasse will be rendered dry enough to be fed to the fires, and my improved apparatus is intended and constructed 20 so as to feed it automatically when in this condition.

Referring to the accompanying drawings, which form a part of this specification, Figure 25 1 is a plan view embodying the principal features of my invention. Fig. 2 is an end elevation, partly in section. Fig. 3 is a partial longitudinal section. Fig. 4 is a detail view of the covers of the conveying pipes or conduits.

30 In the drawings, A is a hopper or receiving-trough provided with feeding-rollers B. Into this hopper is fed the bagasse or refuse cane after it leaves the sugar-mill. After the bagasse or refuse cane passes through the feeding-rollers B, it enters one end of the conduit or canal C. This conduit or canal consists of a cylindrical pipe extending along and outside of one of the boilers D, and connects at its farther end with another conduit or canal of 35 the same cross-section, which extends transversely of the boilers D as far as the outer edge of the farthest boiler. At this point it connects with a third conduit or canal which extends alongside of the last boiler and down 40 to the inner end thereof, where it connects with a fourth conduit or canal which extends along in front of the inner ends of all the boilers. Located within all of these conduits are helical or spirally shaped drivers, which 45 are provided with shafts for rotating the same.

In Fig. 1, at the lower end of the drawings, I show the spirally-shaped driver or worm E,

having the shaft F, the latter being provided at its inner edge with a cog-wheel, G, which gears with the second cog-wheel, H, upon the 55 shaft I. Upon the shaft I are also mounted the pulley-wheels J, which receive the belt for driving the machinery. The shaft I extends laterally along the outside of the conduit or canal C, and is provided at its other end with 60 a beveled wheel, K, which gears with a second beveled wheel, L, the latter being mounted upon the shaft M, which carries the helical or spirally shaped driver N, rotating in the conduit or canal C at the rear end of the boilers. 65 The farther end of the shaft M is provided with a beveled wheel, O, which gears with a smaller beveled wheel, P, the latter being attached to the shaft Q, extending along the other side of the boilers. This shaft Q is provided 70 with a cog-wheel, R, which gears with a second cog-wheel, S, attached to the shaft of driver U, located within the conduit or canal C upon the third side of the boilers.

The cog-wheel G is mounted upon a shaft, 75 G', which is provided with a cog-wheel, G'', which gears with a cog-wheel, G''', mounted on a shaft, G^{IV}, which latter is provided with a beveled wheel, K', gearing with a second beveled wheel, K''. The latter is mounted upon 80 a shaft, V, which extends through the conduit or canal C in the front of the boilers, and upon this shaft is mounted the helical or spirally shaped driver U'.

When the bagasse or refuse cane enters the 85 hopper A, it is acted upon by the feeding and regulating rollers B, which are driven by any suitable source of power, which serve to feed the said bagasse or refuse cane into the conduit or canal C, and by means of the juxtaposition 90 of said rollers to regulate the quantity or amount of the feed at all times. When the bagasse has entered the conduit or canal, it is caught by the rotating helical-shaped driver E, and is conveyed forward in the said conduit or canal as the driver E rotates. When it has reached the end of the first conduit or canal, it discharges into the end of the second conduit or canal, and by means of the driver N is again conveyed forward along the rear ends 95 of the boilers until it reaches the farther end of said conduit. At this point it discharges 100 into the third conduit or canal, extending parallel with the sides of the boilers, and by
